Primary Examiner — Karen S Acker(74) *Attorney, Agent, or Firm* — Banner & Witcoff, Ltd.(57) **CLAIM**

The ornamental design for a chair, as shown and described.

DESCRIPTION

FIG. 1 is a front perspective view of a chair showing my new design;
 FIG. 2 is a rear perspective view thereof;

FIG. 3 is a right side view thereof;

FIG. 4 is a front view thereof;

FIG. 5 is a rear view thereof;

FIG. 6 is a bottom view thereof;

FIG. 7 is a cross-sectional view taken in the direction of line 7-7 in FIG. 3; and,

FIG. 8 is a cross-sectional view taken in the direction of line 8-8 in FIG. 4.

The broken lines shown in the drawings illustrate portions of the chair that form no part of the claimed design.

1 Claim, 6 Drawing Sheets(56)
